John K. Nolan
ATTORNEY

UNITED STATES PATENT OFFICE.

ZAREH H. KEVORKIAN, OF PHILADELPHIA, PENNSYLVANIA.

ELECTRIC ALARM-CLOCK.

SPECIFICATION forming part of Letters Patent No. 703,425, dated July 1, 1902.

Application filed February 12, 1901. Serial No. 46,977. (No model.)

To all whom it may concern:

Be it known that I, ZAREH H. KEVORKIAN, a subject of the Sultan of Turkey, residing in the city and county of Philadelphia and State 5 of Pennsylvania, have invented certain new and useful Improvements in Electric Alarm-Clocks, of which the following is a full, clear, and exact description, reference being had to the accompanying drawings, forming a part 10 of this specification.

This invention relates to electric alarm-clocks; and it has for its object to provide in such a mechanism a novel construction and organization of devices whereby simplicity and 15 ease of setting are combined with accuracy and efficiency of operation, as will be herein-after particularly described and claimed.

In the drawings, Figure 1 is a front elevation of my improved alarm-clock, showing the 20 key in position in dotted lines. Fig. 2 is a vertical section, as on the line 2 2 of Fig. 1, showing the framework only of the clock-movement. Fig. 3 is a sectional detail, as on the line 3 3 of Fig. 2. Fig. 4 is a detail, enlarged, of the hour-hand. Fig. 5 is a view of 25 the key.

A represents a suitable casing in which the clock-movement is contained; B, the framework of the movement; C, a dial, of non-conducting material, affixed to the posts b of the frame, and D D' the arbors for the hour and minute hands d d', respectively. Rotatably fitted within the central aperture of the dial and out of contact with the arbors is the hub 30 e of a spur-wheel E, which lies exteriorly of the dial. This wheel is maintained in place by a centrally-perforated cap or plate e', which is affixed to the hub so as to take frictionally against the inner face of the dial. 35 On the spur-wheel is an arm F, which extends adjacent to the divisions of time on the dial, whereby by the turning of the wheel the arm may be set to any predetermined division indicated on the dial. In the dial adjacent the 40 spur-wheel are orifices c, in either of which may be inserted the barrel of a key G of novel construction. This key is provided at or near the barrel with gear-teeth g, adapted to mesh with those of the spur-wheel E, and 45 thereby facilitate the setting of the arm F. One of the orifices is provided with the usual stem b' for the winding of the clock-spring,

the key being preferably formed at its outer extremity with a socket g', which may be applied to such stem to effect the winding of 55 the spring.

On the under side of the hour-hand d, near the free end thereof, is an antifriction-roller H, which is adapted at a predetermined interval to bear upon the arm F and make electrical contact therewith. To regulate to a nicety the contact of the roller with the arm, I journal the roller in the free end of a flat spring h, that is fastened at its opposite end to the hour-hand, and I provide such hand 60 65 with a set-screw h', that bears upon the spring. Hence by manipulating the screw delicate adjustment of the roller in respect to the plane of the arm F may be effected.

Affixed to the inner face of the dial is a 70 series of spring-fingers I, which bear yielding against the cap of the wheel E to make good electrical contact therewith. These fingers are connected by wires i, as indicated, and are included in an electric circuit, the 75 conductors i i' of which are secured to one of these fingers and to the metallic clock-frame, respectively. While a single spring-finger may be used, I prefer to use several, so as to insure proper electrical contact. 80

In the electric circuit is included an electric alarm-bell J and also a suitable switch j.

By the construction above described it will be seen that if the arm F be set to the division of time when it is desired to sound an 85 alarm and the switch be turned to active position the roller H on the hour-hand will upon reaching the time indicated ride upon and make electric contact with the arm, thereby completing the electric circuit and effecting 90 the sounding of an alarm. As the bell will continue to ring as long as the contact is made, I preferably provide the arm with a lateral extension f in the path of the contact-roller, so that to stop the alarm within a certain 95 interval of time it is necessary to move the switch to break the electric circuit.

I claim—

1. In an alarm-clock of the character described, the combination of the hour-hand, 100 the dial, the arm in the path of said hand, the central spur-wheel carrying said arm, the key provided with teeth adapted to engage those of the spur-wheel, a contact-spring bearing

against said wheel, the electric alarm, and the normally broken circuit therefor connected with said contact-spring and with the clock-movement, substantially as described.

5 2. In an alarm-clock of the character described, the combination of the hour-hand, the apertured dial, the arm in the path of said hand, the central spur-wheel carrying said arm, the separate key adapted to be fitted to the aperture of the dial and provided with teeth to engage those of the spur-wheel, a contact-spring bearing against said wheel, the electric alarm, and the normally broken circuit therefor connected with said contact-

15 spring and with the clock-movement, substantially as described.

3. In an alarm-clock of the character described, the combination of the hour-hand, a flat spring one end of which is secured to said hand, an antifriction-roller journaled in the free end of said spring, and a set-screw fitted to the hand and bearing against the spring,

the electric alarm, the normally broken circuit therefor, a setting-arm in said circuit, a spur-wheel carrying said arm, and a toothed key for engaging and turning said spur-wheel, substantially as described. 25

4. In an alarm-clock of the character described, the combination with the hour-hand, the dial of non-conducting material, the arm in the path of said hand, the central wheel or support for said arm, a contact-spring affixed to the dial and bearing against said wheel or support, the electric alarm, and the normally broken circuit therefor connected with said contact-spring and with the clock-movement, 30 substantially as described. 35

In testimony whereof I have hereunto affixed my signature in the presence of two subscribing witnesses.

ZAREH H. KEVORKIAN.
